UNITED STATES PATENT OFFICE.

STUART B. LAFEAN, OF YORK, PENNSYLVANIA.

CARAMEL-HOLDER.

945,788.

Specification of Letters Patent. Patented Jan. 11, 1910.

Application filed September 3, 1909. Serial No. 516,116.

To all whom it may concern:

Be it known that I, STUART B. LAFEAN, a citizen of the United States, and resident of York, in the county of York and State of Pennsylvania, have invented certain new and useful Improvements in Caramel-Holders, of which the following is a specification.

This invention relates to caramel holders of the general type disclosed in the patent 10 to Wiest, No. 428,765, May 27, 1890. It includes sheets, preferably made of tin, having thereon upright rows of flanges in pairs running longitudinally and transversely of the sheet, and each row being out of line 15 with the flanges of the rows running at right angles.

The object of the invention is to simplify the manufacture of the plates designed to contain the caramels in rows separated from 20 each other, and at the same time to provide means for preventing the caramels from being accidentally displaced.

The novel features of the invention will be apparent from the following description 25 taken in connection with the drawing.

In the drawing,—Figure 1 is a perspective view partly broken away of a sheet embodying my invention; Fig. 2 is a sectional view of several sheets placed in position one above 30 the other.

In these drawings 1 represents the sheet which is preferably made of tin and which contains rows of flanges 2, 3, extending parallel to one edge of the plate and rows of 35 flanges 4, 5 extending at right angles to the first mentioned flanges. The flanges 4 and 5 are entirely between the rows of flanges 2, 3 and the separate flanges 2 and 3 are entirely between the rows 4 and 5. By this arrangement there is formed a rectangular space 6 partially surrounded by the flanges 2, 3, 4 and 5 and of such size as to receive a caramel. As will be seen by reference to the drawing there are a series of such spaces 40 in line with each other, but separated so that each caramel will be held separately. The flanges 2, 3, 4 and 5 are each formed by cutting out and bending up a small portion of the sheet within the margin of the space 45 6 which receives the caramel, so that there will be openings 7 beneath the caramel when it is placed in position. These flanges are

preferably bent up by the punching operation, and since each one is entirely independent of all the others and as the hole formed by punching one flange has no connection with any hole formed by punching any other flange, it is possible by one operation to punch all of the flanges on the sheet, thus simplifying the necessary operation in making the sheet. It is cheaper to make the plate where all of the flanges can be punched by one operation than where separate strokes are required for different flanges.

In addition to the advantages in the process of manufacture the punching of the flanges separately from the sheet within the margin of the caramel space has the additional advantage of providing openings in the sheet beneath the caramel which serve to hold the caramel more firmly in place on the sheet, so as to prevent accidental displacement.

The caramel when soft will sink down into the opening 7 to a certain extent, but not 75 enough to prevent lifting the caramel out easily when desired.

The several sheets in the package are spaced apart so that one will not rest upon the caramels on the other by angular supports 8, preferably made of tin, and which are removable.

Having thus described the invention, what is claimed is:

1. A caramel holder consisting of a sheet 85 having rows of rectangular caramel receiving spaces, each space having central at its sides and ends vertical flanges extending throughout a part of its length, cut independently from the sheet within the space and 90 bent at right angles thereto.

2. A caramel holder consisting of a sheet having rows of rectangular caramel receiving spaces, each space having at its sides and ends vertical flanges cut from the sheet within the space and bent at right angles thereto 95 whereby there will be openings through the sheet within the caramel spaces.

In testimony whereof I affix my signature in presence of two witnesses.

STUART B. LAFEAN.
